UNITED STATES PATENT OFFICE.

JAMES W. PROVAN, OF OSHAWA, ONTARIO, CANADA.

GOLF-CLUB.

1,071,344.

Specification of Letters Patent. Patented Aug. 26, 1913.

Application filed April 2, 1912. Serial No. 687,962.

To all whom it may concern:

Be it known that I, JAMES W. PROVAN, of the town of Oshawa, in the Province of Ontario, Canada, have invented certain new 5 and useful Improvements in Golf-Clubs, of which the following is a specification.

This invention relates particularly to improvements in the grip portion of the shaft of a golf club.

10 Among numerous factors necessary to success in playing golf, two, depending on the holding of the club are of special importance. These are, accuracy of alinement, and security of grasp. That is to say, the shaft 15 must be held so that the face of the head bears a certain angular relationship to the grasp of the hand, otherwise the ball will not be struck fairly; and the shaft must not twist in the hands or pull through them 20 when the ball is struck, otherwise the advantage of the original accurate alinement is at once lost.

In the ordinary club, accuracy of alinement depends entirely on the judgment of 25 the player, and security of grip depends on the firmness of his grasp aided, perhaps, by a little wax.

30 My object, therefore, is to devise a form of grip for a golf club which will give accurate alinement independent of the player's eye and by the sense of feeling, and which will give the desired security of grasp.

I am aware that attempts have been made to fit the grip to the hands of the user, or 35 to provide protuberances to give security of grasp, but such constructions either completely deprive the player of his freedom to shift his grip up or down the grip portion of the shaft, or cramp him when the hands 40 need to relax their rigid correctness of position, at the top of the backward swing, or give no sense of correct alinement by feeling.

I attain my object by providing the grip 45 with a series of uniform transverse finger grooves, formed at one side of the upper part of the grip portion of the shaft, to receive the terminal phalanges of the fingers of the upper hand only, at variable positions 50 along the shaft the said grooves being substantially straight in the direction of their length, and curved longitudinally of the shaft. I place the grooves on the side of the shaft in such relation to the driving face of 55 the club, that they will give the club its correct alinement. I also make the grooves,

preferably, six in number, allowing the player full benefit of the use of the grooves with either a long or short grip of the club. The grooves being substantially straight in 60 the direction of their length will prevent the club from turning in the hand and also prevent the club from slipping through the hand. This improved grip is adapted for players using the favorite "overlap grip" 65 as well as for players continuing to use the ordinary "open grip".

The upper hand is the controlling hand in holding the club in alinement, and as 70 only the terminal phalanges of that hand rest in the grooves, the sense of correct alinement by feeling is obtained by that part of the hand which possesses the most delicate sense of touch and also sufficient power to accomplish the object desired, leaving a 75 necessary amount of freedom for the other parts of the said upper hand, while the lower hand is unrestrained in any way.

To obtain the most satisfactory results I 80 find it necessary to have the center of that portion between the grooves about one-eighth of an inch above the line of the normal circumference of the grip, in which case it is impracticable to carve out the grooves in the wood of shafts already made, hence 85 I make a plate, preferably of aluminum on account of its lightness, hardness, and durability, on which I form the grooves, which plate is placed securely on the shaft and under the wrapping, as shown in the drawings, I find that aluminum can be cast sufficiently thin for my purpose, with perfectly uniform and correctly formed grooves, a result unattainable by individual carving, and at less cost of production. 90

95 In the accompanying drawings: Figure 1. is an elevation of the club with the head turned somewhat toward the observer to bring the special grip into side elevation. Fig. 2 is a longitudinal section of the grip portion of the shaft on an enlarged scale. Fig. 3 is a front elevation on the same scale as Fig. 2, and Fig. 4 an end view with the grip in section.

100 In the drawings, like numerals of reference indicate corresponding parts in the different figures.

105 Referring to Fig. 1 I show an iron head 1 and a shaft 2 of ordinary form save for a special configuration given to the grip portion 3. The grip 3, while mainly substantially circular in cross section and tapered 110

as usual is provided toward its rear side with a plurality of transverse grooves 4 which are substantially straight in the direction of their length and preferably 5 curved longitudinally of the shaft. The direction of the length of these grooves is inclined at an angle of between 30° and 40° toward a plane touching the lower edge of the face of the head and substantially parallel 10 to the axis of the shaft, see Fig. 4. (For most players 33° will be found to be the right angle). Thus, when the terminal phalanges of the fingers of the upper hand engage properly on the flat bottoms of the 15 grooves, the shaft is then so related to the grasp that the head is exactly at the proper angle for the stroke.

It should be noted that correct alignment can be obtained if two grooves only are 20 straight in the direction of their length, say those for the middle and ring fingers only, but as at different times it is desirable to be able to play with a long or short club, it is preferable to make all the grooves 25 straight and to make then five or six in member, so that the grip may be grasped closer to or farther from the head as may be desired.

While the shaft itself, if thick enough, 30 might be curved to the desired shape, it is simpler to form the grooves in a separate plate 5, say of aluminum or hard rubber, and to secure the plate to the shaft. (See 35 Figs. 2, 3 and 4). Afterward the plate and shaft may be wrapped in the ordinary way, as shown in Fig. 1.

In fitting up a club according to my invention, the shaft will first be fitted to the head with the natural spring in the right direction. The club will then be laid on a 40 flat surface, (see Fig. 4), and by means of any suitable tool the correct angle for the plate is laid out. The shaft is then suitably flattened to receive the plate which is 45 secured in place as shown and subsequently wrapped.

In using the club as hereinbefore mentioned, the terminal phalanges of the fingers, or at any rate of the middle and ring

fingers of the upper hand lie flat in the 5 grooves so that the shaft occupies a predetermined position in the hand which automatically gives the correct alignment for the head. It is evident, also, that as the finger ends of the upper hand lie in grooves that 10 the grip will not pull through the hands and the resistance to the twisting of the grip in the hands is greatly increased. As the notches make it impossible to grasp the 15 club except in certain predetermined positions, the player can always be sure that he is securing the effective length of club which his experience tells him is best for a certain play.

At the top of a backward swing the hands 65 must have liberty to change somewhat from the position they assume when the ball is struck. In this club the hands may shift as much as may be necessary without the 70 terminal phalanges of the fingers losing their position in the grooves, so that at all times the feeling of alignment is given.

What I claim as my invention is:—

1. A golf club having a series of uniform 75 transverse finger grooves formed at one side of the upper part of the grip portion of the shaft to receive the terminal phalanges of the fingers of the upper hand at variable 80 positions along the shaft, the said grooves being substantially straight in the direction 85 of their length and curved longitudinally of the shaft.

2. A golf club having a plate applied to one side of the grip portion of the shaft, 90 said plate having a series of uniform transverse finger grooves formed therein to receive the terminal phalanges of the fingers of the upper hand at variable positions along the shaft, the said grooves being substantially straight in the direction of their length, and a wrapping of flexible material bound over said grip portion and the plate.

Dated at Toronto this 30th day of March, 1912.

JAMES W. PROVAN.
